US00D718490S

(12) **United States Design Patent**
Castillo

(10) **Patent No.:** **US D718,490 S**
(45) **Date of Patent:** **** Nov. 25, 2014**

(54) **LED LENS**

(71) Applicant: **Cree, Inc.**, Durham, NC (US)

(72) Inventor: **Mario Alberto Castillo**, New Braunfels, TX (US)

(73) Assignee: **Cree, Inc.**, Durham, NC (US)

(**) Term: **14 Years**

(21) Appl. No.: **29/449,434**

(22) Filed: **Mar. 15, 2013**

(51) LOC (10) Cl. **26-99**

(52) U.S. Cl.

USPC **D26/120**

(57) **CLAIM**

The ornamental design for an LED lens, as shown and described.

DESCRIPTION

FIG. 1 is a transparent top perspective view of the LED lens; FIG. 2 is a transparent bottom perspective view of the lens of FIGURE;

FIG. 3 is a transparent top plan view of the lens of FIG. 1; FIG. 4 is a transparent bottom plan view of the lens of FIG. 1; FIG. 5 is a transparent left side elevation of the lens of FIG. 1, the right side elevation being a mirror image thereof;

FIG. 6 is a transparent front elevation of the lens of FIG. 1; FIG. 7 is a transparent back elevation of the lens of FIG. 1; FIG. 8 is an opaque top perspective view of the lens of FIG. 1; FIG. 9 is an opaque bottom perspective view of the lens of FIG. 1;

FIG. 10 is an opaque top plan view of the lens of FIG. 1; FIG. 11 is an opaque bottom plan view of the lens of FIG. 1; FIG. 12 is an opaque left side elevation of the lens of FIG. 1, the right side elevation being a mirror image thereof;

FIG. 13 is an opaque front elevation of the lens of FIG. 1; FIG. 14 is an opaque back elevation of the lens of FIG. 1; FIG. 15 is a side-to-side sectional view taken along the middle of the lens of FIG. 1; and,

FIG. 16 is a front-to-back sectional view taken along the middle of the lens of FIG. 1.

The phantom lines illustrating portions of the LED lens are provided for illustrative purposes only and form no part of the claimed design.

1 Claim, 7 Drawing Sheets
